UNITED STATES PATENT OFFICE.

HAROLD W. FLETCHER, OF HOUSTON, TEXAS, ASSIGNOR OF ONE-THIRD TO J. E. SCHROEDER, OF HARRIS COUNTY, TEXAS.

HEAT EXCHANGE.

Application filed May 20, 1922. Serial No. 562,306.

To all whom it may concern:

Be it known that I, HAROLD W. FLETCHER, a citizen of the United States, residing at Houston, Harris County, Texas, have invented a certain new and useful Improvement 5 in Heat Exchanges, of which the following is a full, clear, and exact description, such as will enable others skilled in the art to which it appertains to make and use 10 the same.

My invention relates to a process of transferring heat from a hot liquid chemically impure, to another liquid not so contaminated with impurities, in such manner that 15 the latter liquid shall not be mixed with or contaminated by the hot liquid.

In the mining of sulfur it is customary to drill wells downwardly into the earth to the sulfur stratum and to then discharge 20 hot water into the sulfur stratum at a temperature high enough to fuse the sulfur. The sulfur in its fused condition may then be pumped out of the well by the well known Frasch process. It is usual to find 25 the sulfur stratum close to, or impregnated with, a quantity of cold subterranean water. To obtain the large quantities of sulfur in the pay stratum, it thus becomes necessary to heat up the body of cold water adjacent 30 to the sulfur, by circulating into the well large quantities of hot water. In order to keep up the circulation of the hot water into the sulfur stratum, other wells may be drilled some distance from the first well to allow 35 the passage out of the sulfur bed of the water thus pumped into the earth. These discharge wells are called "bleed" wells and the water thus being discharged from such wells is usually at a high temperature. Said 40 bleed water is contaminated with numerous chemical impurities coming from the sulfur and from other formation with which the water comes in contact during its passage through the earth. The bleed water is thus 45 so impure that it can not be used again due to the fact that it will corrode the pipes and fill them with scale, and this bleed water with its great heat content is now discharged to waste.

50 It is an object of my invention to transfer the heat from this chemically impure hot liquid to a second fresh liquid without contaminating the liquid to be heated with the impurities from the said hot liquid.

55 More specifically, I purpose to utilize the

heat from the bleed water discharged from a sulfur mine, without mixing the liquid to be heated with the bleed water, and without the corrosion and blocking of the apparatus by the impurities in the bleed water. 60

Another object is to provide an apparatus for heating fresh water by means of the chemically impure hot bleed water without contaminating the said fresh water, and to perform this process in a manner practically 65 continuous, and to provide an effective apparatus for carrying out the process.

Other objects and advantages of my improved process and apparatus will be obvious to those skilled in the art, from the 70 more detailed description thereof which follows:

Referring to the drawing herewith, I have shown, more or less diagrammatically, the installation of an apparatus by means of 75 75 which my invention may be carried out, part of said apparatus being shown in central vertical section for greater clearness.

The impure water discharged from the bleed well is conducted through a discharge 80 pipe 1, into a tank or vat 2. In the upper part of said vat, which is preferably made of wood or other chemically resistant material, I have fixed a receiving container 3, also made of wood, into which the water is 85 discharged. The bottom of this container is perforated at 4 so as to discharge the bleed water with some force, in small jets or sprays, downwardly into the vat. Below the said container 3 within the tank I have 90 shown a quantity of oil or other non-miscible light gravity liquid 5. While I have described the use of oil because of its cheapness and convenience, I contemplate using any similar liquid having a different spe- 95 cific gravity than that of the bleed water, so that the two liquids will separate easily after being mixed. In this case, the water being heavier than the oil, will be mixed therewith and settle downwardly through 100 the oil into the bottom of the tank. The heat of the bleed water will be thereby communicated to the oil during the passage of the water therethrough. The cooling of the bleed water by contact with the cold oil 105 will cause the precipitation from the water of a large part of the impurities therein. This precipitate will settle in the form of flakes or small particles, to the bottom of tank, 2, where it can be drawn off. For the 110

purpose of carrying off this cooled water together with the impurities therein, I provide a lower outlet pipe 6, having a valve 7 therein to control the rate of flow from the 5 tank.

The oil thus heated will be conducted from the tank 2 through a lateral pipe 8 having a valve 9 to control the flow, to the adjacent settling tank 10. This tank is 10 preferably made of wood and has transverse baffle plates 11 extending across the same as shown in the drawing, one of these plates being extended above the level of the oil and another plate extending to a point adjacent 15 the bottom of the tank and below the lower level of the oil. The heated oil would thus be constrained to pass downwardly around the lower end of the first baffle 11 and upwardly over the top of the second baffle 12, and from thence to an outlet pipe 13. In this passage through the settling tank particles of acid, water and sediment would tend to settle out into the bottom of the tank where they may be drawn off 20 through an outlet pipe 14, as desired.

The heated oil, passing outwardly through the pipe 13 from the settling tank, may be forced by the rotary pump 15 through a strainer. This strainer may be of any 30 commercial type and I have shown the same somewhat diagrammatically at 16 in the drawing. From this strainer, which is adapted to remove any particles of scale or sediment from the oil, the said oil 35 will pass into the upper end of a heater 17 by way of the pipe 18.

The heater 17 may be of any commercial type and the heated oil may pass downwardly through pipes in the heater, about 40 which pipes may be circulated the liquid to be heated. The pure water will be pumped into the lower end of the heater 17 through the pipe 19. It will pass upwardly over the pipes in which the heated oil is 45 conducted, and thus abstract the heat from the oil flowing through the pipes. The heated water, after passing over the pipes, will be discharged at 20 through a pipe leading to the fresh water container, not shown. The oil, after passing through the 50 heater, will be thus cooled and will find an outlet through a pipe 21 back to the tank 2 and will be discharged at 22 at a point in the tank approximately level with the lower surface of the oil therein. A check 55 valve 23 in the pipe 21 may serve to close the said pipe and prevent the rising of the level of the oil in the tank 2 during the period when the device is not in operation. 60 While I have described the oil as passing through the heater 17 through pipes therein, it is obvious that the oil may be discharged freely into the said container 17 and the water to be heated may be conducted 65 through pipes in the heater over

which the heated oil will pass. Either of these modifications are understood to be old in the ordinary type of commercial heater, and I do not wish to be confined to the form described.

While the greater part of the acids contained in the bleed water from the mine will settle out during the cooling of the bleed water as it passes through the oil in tank 2, a certain amount of the acid may be held in 75 more or less emulsified condition with the oil and pass in small globules suspended in the oil, into the tank 10, and in order to facilitate the settling out of the acids, and to neutralize the same as far as possible, I 80 may attach toward the upper end of the tank 10 a small container 24 for some neutralizing agent which may be discharged gradually into the oil through an inlet pipe 25 there shown. This pipe may be controlled by a 85 valve 26 so that the required amount of the alkali or other agent may be mixed with the oil to assist in the settling of the impurities during the passage of the oil through the settling tank. It is contemplated that gage 90 glasses 27 may be placed upon the side of the tank 2 and gage glass 28 be placed upon the tank 10 in such position as to indicate to the operator the level of the liquids in the tank.

In the operation of my device, the bleed water from the mine will be discharged through the perforated container 3 under sufficient head to spray the same into the body of oil 5 in tank 2. The heated water passing in small globules downwardly 100 through the oil, will give up its heat to the oil, and as it cools, the impurities in the bleed water will be partly precipitated out and will be carried downwardly with the cold water to the bottom of the tank and 105 will be discharged with the water through the outlet pipe 6. The oil thus heated by the bleed water will pass through the settling tank in the manner described and be forced by the pump 15 through the heater 17 where the heat from the oil will be transferred to the water. Said water will then be further heated with live steam and pumped into the mine to melt more sulfur. The oil, after being cooled will be forced through the 110 return pipe 21 to the tank 2 to be again used in the manner described. The water passing from the heater through the pipe 20 may then be used in conjunction with other heated water to be discharged again into the mine 115 for use.

The advantages of this particular process lie in the efficient manner in which the heat is transferred from the bleed water to the oil. There will be no chance in this method, 120 for deposit of scale upon the pipes of the apparatus, as the scale or other sediment will be precipitated by cooling in the passage of the water through the oil and will settle in the bottom of the tank in such condition that 125

it may be flushed out with the discharge water, through the pipe 6. Most of the acid contained in the water will also settle out and be discharged. Any small particles remaining and tending to corrode the apparatus, will be settled out in the tank 10 and will be neutralized, if desired, through the neutralizing agents discharged into the oil from the container 24. Very little sediment will 5 find its way through the pump to the strainer. Such as may remain in the oil will be removed in the strainer. It is possible therefore, to operate this process with very little injury to the installation, and one set of apparatus may be operated for long periods without the necessity of replacement. Further objects and advantages of this invention will be obvious to one skilled in the art without further description.

10 What I claim is new and desire to protect by Letters Patent is:

1. The process of transferring heat from an impure hot liquid to a colder fresh liquid comprising passing the hot impure liquid 15 through a cooler non-miscible intermediate liquid of different specific gravity and adapted to absorb heat therefrom, separating the then cooled impure liquid together with its impurities from said intermediate liquid, and finally transferring the heat from said intermediate liquid to said fresh liquid by 20 means of a heater.
2. The process of transferring heat from an impure hot liquid to a colder fresh liquid comprising bringing the hot impure liquid 25 into intimate contact with a mass of cooler oil, separating the then cooled impure liquid together with its impurities from said oil, and finally transferring the heat from said oil to said fresh liquid by means of a heater.
3. The process of transferring heat from an impure hot liquid to a colder fresh liquid comprising bringing the hot impure liquid 30 into intimate contact with a non-miscible liquid of lighter specific gravity than said impure liquid and adapted to absorb heat therefrom settling out by gravity the then cooled impure liquid and finally transferring the heat from said light liquid to said fresh liquid.
4. The process of transferring heat from

hot contaminated bleed water to relatively cold fresh water comprising bringing said bleed water into contact with a non-miscible liquid of lighter specific gravity, settling out 55 the cooled bleed water and transferring the heat from said lighter liquid to said fresh water by pumping said lighter liquid into contact with a heat conducting container for said fresh water substantially as described.

5. The process of transferring heat from hot impure bleed water to cold fresh water comprising bringing said hot bleed water into intimate contact with oil, acting to absorb the heat therefrom, separating said impure bleed water from the oil, and passing 60 said heated oil into close relation with said cold fresh water whereby said fresh water is heated.

6. The process of transferring heat from 70 an impure hot liquid to another uncontaminated liquid comprising passing said hot liquid through a quantity of oil whereby the heat is absorbed in said oil, settling the liquid and impurities from the oil, and 75 bringing said heated oil into contact with the container for said uncontaminated liquid and drawing off the last named liquid.

7. In an apparatus for heat exchange for liquids, a tank, a spraying device therein, a head of oil in said tank below said spraying device, an outlet below said oil, a settling tank, a pipe connecting said tanks, a heater, connecting pipes between said settling tank, and said heater, and a pump in one of said connecting pipes in the manner described.

8. The process of transferring heat from an impure hot liquid to a colder fresh liquid, consisting of first mixing the impure hot liquid with a cold intermediate non-miscible 90 liquid of different specific gravity to which the heat is transferred, separating the then cooled impure liquid, together with its impurities, from the intermediate liquid, and then transferring the heat by conduction 95 from said intermediate liquid to said fresh liquid.

In testimony whereof, I hereunto affix my signature, this the 16th day of May, A. D., 1922.

HAROLD W. FLETCHER.
